Patented Oct. 10, 1922.

Inventor:
Benjamin W. Jones,
by Albert S. Davis
His Attorney.

UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

CIRCUIT CONTROLLER.

Application filed November 26, 1921. Serial No. 518,031.

To all whom it may concern:

Be it known that I, BENJAMIN W. JONES, a citizen of the United States, residing at Schenectady, in the county of Schenectady, 5 State of New York, have invented certain new and useful Improvements in Circuit Controllers, of which the following is a specification.

My invention relates to an improved arrangement for controlling the connection of electric translating devices to the source of supply.

One of the objects of the invention is to provide an arrangement involving the use of 15 two electroresponsive line switches which are successively closed only in case the conditions in the controlled circuit are such that it is safe for the translating device or devices in the controlled circuit to be connected 20 to a source of supply. It has heretofore been proposed to close the electroresponsive line switches successively, since if a dangerous condition should be present in the controlled circuit and the contacts of the last line switch 25 to close should be welded shut, the first line switch to close is nevertheless free to open in response to the operation of a current responsive means. It has also been proposed that the arrangement should be such that 30 after the first line switch is thus opened, it shall be prevented from being reclosed until after the second line switch has been opened, thereby preventing the welding shut of the contacts of both line switches.

35 My invention is directed to improvements of circuit controllers of this general nature. In accordance with my invention, if after the first line switch is closed, the conditions of the controlled circuit are such that the second line switch should not be permitted to close, it is prevented from being closed until the dangerous condition is removed. Since the controlled circuit can not be connected to the source of supply unless it is safe to 40 do so, the contacts of both line switches are prevented from being welded shut. Furthermore, the arrangement is such that in case the line switches are automatically opened in response to an abnormal condition in the 45 controlled circuit, the first line switch will

not reclose until the operator intends that it shall be closed.

In carrying my invention into effect, I provide a master controller for the line switches which may be manually or otherwise operated, and an electroresponsive relay for controlling the second line switch to close. The relay winding is connected across the controlled circuit both before and after the line switches are closed, but when 55 the first line switch closes, the relay winding is connected in series with a resistor which is connected across the contacts of the second line switch, so that in case there is a low resistance path in the controlled circuit, due, 60 for instance, to a controller for one of the translating devices in the controlled circuit being left in a running position, the relay will not be energized sufficiently to close and thereby energize the second line switch to 65 close, since the relay winding will be connected in multiple with the low resistance path of the controlled circuit.

70 For a better understanding of the invention, reference is had to the accompanying drawing wherein I have illustrated one embodiment of the invention for the purpose of explaining the principles thereof. Referring to the drawing, the circuit to be controlled has included therein a plurality of 75 electric translating devices, indicated by the armatures 10, 11 and 12 of electric motors. Each of these electric motors is provided with a separate controller 13, 14 and 15 respectively. The electroresponsive line 80 switches 16 and 17 are provided for connecting the controlled circuits to the source of supply 18. A master controller 19 is provided for manually or otherwise controlling the closing of the line switches 16 and 17, 85 and an electroresponsive relay 20 is provided for controlling the closing of the line switch 17. The winding of this relay is normally connected across the controlled circuit, and the arrangement is such that after the line 90 switch 16 is energized to close by the closing of the master switch 19, the resistor 21 is connected across the switch contacts of the line switch 17, and the winding of the relay 95 20 is connected in series with the resistor 21 100

across the supply circuit. The energization of the winding of relay 20 is therefore indirectly responsive to the voltage drop across the contacts of line switch 17, the 5 second switch to close, and directly responsive to the resistance of the controlled circuit, so that unless the controlled circuit is either open or the resistance thereof is high, the relay 20 will not be energized to 10 close and thereby energize the line switch 17 to close.

As thus constructed and arranged, and with the parts in their respective positions shown in the drawing, the operation of my 15 invention is as follows:—The disconnecting switch 22 will first be closed and then the pilot switch 23. It is assumed that the controllers 13, 14 and 15 are in their respective off positions and that no dangerous condition 20 is present in the circuit of any of the translating devices. In order to close the line switches 16 and 17, the master switch or push button 19 is closed, thereby energizing the winding of the line switch 16 25 through a circuit including the conductor 24, conductor 25, conductor 26, winding of line switch 16, through the contacts of the current protective relays 27, 28, 29 and 30, to the other supply conductor. With the 30 push button 19 in the closed position, the resistor 21 is connected across the contacts of the line switch 17 through a circuit including the conductors 24 and 25 and the contacts of the push button 19. The winding 35 of the relay 20 is connected in series with the resistor 21 across the supply circuit through the contacts of the line switch 16. This relay is therefore energized indirectly 40 responsive to the voltage drop across the line switch 17 and directly responsive to the resistance of the controlled circuit. It has been assumed that the controllers 13, 14 and 15 are all in their respective off positions, and that no dangerous condition 45 is present in the circuits of the translating devices 10, 11 and 12, so that the voltage drop across the winding of the relay 20 is substantially the voltage of the supply circuit, and the relay 20 will thereby be energized to close and complete the winding 50 circuit for the line switch 17. The line switch 17 will thereupon close and connect the controlled circuit to the source of supply. The auxiliary switch 31 connected 55 with the line switch 17 is provided for short circuiting the contacts of the push button 19, so that this push button may be released and the line switch nevertheless remain energized and closed.

60 In order to connect the motor armatures 10, 11 and 12 to the source of supply, the respective controllers 13, 14 and 15 will be turned to the operative positions. In case 65 an overload or some dangerous electrical condition should occur in the circuit of the

motor armature 10, the current relay 28 will be energized sufficiently to pick up its contacts and open the circuit for the windings of the line switches 16 and 17. The current relay 28 will drop its contacts when the line switches are open, but the controlled circuit will not be reconnected to the source of supply. That is because of the fact that the master switch or push button 19 is in the open position. If all the controllers 70 13, 14 and 15 are not returned to their respective off positions, the line switch 17 is prevented from being reclosed by the operation of the master switch 19. Thus, closing the master switch 19 will energize the line switch 16 to close as before, but the winding of the relay 20 will not be sufficiently energized to close, and the winding of the line switch 17 is thereby prevented 75 from being energized. That is because of the fact that the resistor 21 is connected in series with a multiple circuit having the relay winding in one branch and the circuit or circuits through the translating device or devices in another branch or branches. 80 The operator is thus warned that some dangerous condition is present in the controlled circuit, and his attention will be called to the fact that probably one or all of the controllers 13, 14 and 15 are not in their respective off positions. He will then remember to return the controllers to their respective off positions before again attempting to connect the controlled circuit to the source of supply. If the controllers 85 13, 14 and 15 are returned to their respective off positions the low resistance shunt around the winding of the relay 20 is removed so that operating the master switch 19 will energize the line switch 16 to close 90 as before and the relay 20 will thereby be energized to close its contacts and energize the line switch 17 to close as previously explained. If the line switch 17 is closed, the relay 20 is energized across the controlled circuit so as to maintain the energization of the line switch 17 until a dangerous condition occurs in the controlled circuit. If, for example, there should be a short circuit condition in the armature 95 10 when the operator moves the controller 13 from the off to an operative position, the current relay 28 will be energized to open and thus cause the line switches 16 and 17 to open as previously explained. The operator is thus apprized of the fact that 110 there is a dangerous condition in this circuit, and he will know that before he can continue with the operation of the motors 11 and 12, this dangerous condition 115 must be removed. It will also be observed that the arrangement prevents the closing of both line switches in case there should be a short circuit between the conductors 120 of the controlled circuit, even though the 125 130

controllers are in their off positions. Furthermore, it is not necessary to run any wires to the separate controllers other than the main conductors in which the translating devices are included.

In accordance with the provisions of the patent statutes, I have described the principle of operation of my invention, together with the apparatus which I now consider 10 to represent the best embodiment thereof, but I desire to have it understood that the apparatus shown is only illustrative and that the invention may be carried out by other means.

15 What I claim as new and desire to secure by Letters Patent of the United States, is:—

1. The combination in a circuit controller of two normally open electroresponsive line switches, a master controller therefor, an 20 electroresponsive relay for controlling the second of said line switches, and connections whereby the operation of the said master controller energizes the first line switch to close and energizes the winding of 25 the said relay responsively to the resistance of the controlled circuit so that the relay will subsequently automatically operate and energize the second line switch to close only in case the resistance of the controlled circuit is above a predetermined value.

2. The combination in a circuit controller of two normally open electromagnetic line switches, a master controller therefor, a normally open electromagnetic relay for controlling the second of the said line switches, and connections whereby the operation of the said master controller energizes the first line switch to close and energizes the winding of the said relay responsively to the resistance of the controlled circuit so that the relay will subsequently automatically close and energize the second line switch to close only in case the resistance of the controlled circuit is above a predetermined 45 value.

3. The combination in a circuit controller of two normally open electromagnetic line switches for controlling the connection of a translating device to a source of supply, 50 a master controller for the said line switches, an electromagnetic relay having its winding connected across the circuit controlled by the said line switches for controlling the second of said line switches, and connections whereby the operation of the said master controller energizes the first line switch to close and thereby connects the winding of the said relay across the switch contacts of the second line switch in multiple with a translating device in the controlled circuit so that the relay will automatically close and energize the second line switch to close only in case the resistance of the controlled circuit is above a predetermined value.

65 4. The combination in a circuit controller

of two normally open electromagnetic line switches, a master controller therefor, an electroresponsive relay controlling the second of the said line switches, and connections whereby the operation of the said master controller energizes the first line switch to close and the said relay is then energized to operate responsively to a predetermined voltage drop across the switch contacts of the second line switch to energize the second line switch to close.

5. The combination in a circuit controller of two normally open electromagnetic line switches for controlling the connection of a translating device to a source of supply, a 80 master controller for the said line switches, an electromagnetic relay having its winding connected across the circuit controlled by the said line switches for controlling the second of said line switches, a resistor, and 85 connections whereby the operation of the said master controller energizes the first line switch to close and thus connect the said resistor across the contacts of the second line switch and the winding of the said relay in a multiple circuit with the said translating device, with the said multiple circuit in series with the said resistor across the source of supply so that the said relay will automatically close and energize the 90 second line switch to close only in case the resistance of the controlled circuit is above a predetermined value.

6. The combination in a circuit controller of two normally open electromagnetic line 100 switches for controlling the connection of a translating device to a source of supply, a separate controller for the said translating device, a master controller for the said line switches, an electromagnetic relay for controlling the second of said line switches, a resistor, and connections whereby the operation of the said master controller energizes the first line switch to close and thus connect the said resistor across the contacts of the second line switch and the winding of the said relay in multiple with a circuit through the said separate controller in series with the said resistor across the source of supply so that the said relay will 110 automatically close and energize the second line switch to close only in case the said controller is operated to open the circuit through the said translating device.

7. The combination in a circuit controller 120 of two normally open electromagnetic line switches for controlling the connection of a plurality of translating devices to a source of supply, a separate controller for each of said translating devices, a master controller 125 for the said line switches, an electromagnetic relay having its winding connected across the circuit controlled by the said line switches for controlling the second of said line switches, a resistor, and connections 130

whereby the operation of said master controller energizes the first line switch to close and thus connect the said resistor across the contacts of the second line switch and the winding of the said relay in multiple with whatever circuits through the translating device are established by the said separate controllers, with the said multiple circuit in series with the said resistor across the

source of supply so that the said relay will 10 automatically close and energize the second line switch to close only in case the circuit or circuits through the said translating devices are opened by the operation of the said separate controllers.

In witness whereof, I have hereunto set my hand this 25th day of November, 1921.

BENJAMIN W. JONES.
